UNITED STATES PATENT OFFICE

CHARLES E. STRONG, OF PARIS, FRANCE, ASSIGNOR TO WESTERN ELECTRIC COMPANY,
INCORPORATED, OF NEW YORK, N. Y., A CORPORATION OF NEW YORK

VACUUM TUBE CIRCUITS

Application filed September 11, 1930, Serial No. 481,094, and in Great Britain December 5, 1929.

This invention relates to wave translation systems and particularly to amplifying circuits utilizing electron discharge tubes.

Hitherto in amplifying systems it has been usual, when great amplification has been required, to connect a number of vacuum tubes in parallel. A difficulty experienced in such arrangements has been to provide for the grid excitation to be equal on each of the tubes and for each tube to work into a similar plate impedance. This has been particularly noticeable in systems for amplifying very high frequencies of the order of 20 megacycles and it has been proposed to mount the tubes very close together to overcome this difficulty but due to the close proximity of the tubes under such conditions spurious oscillations have been set up due to the intercoupling between the tube electrodes. Up to the present, therefore, there has been a limit to the number of tubes which may be connected in parallel, which for the very high frequencies already referred to has been about three or four and this obviously limits the total amplification it is possible to obtain.

In order to increase the number of tubes and thus the possibility of handling greater power, it has also been proposed to arrange in push-pull two sets of parallel connected tubes. While this arrangement certainly doubles the limit of the number of tubes it is possible to use, there has also been a limit in this arrangement which limit for very high frequencies has been six or eight, that is, three or four in each part of the push-pull arrangement.

It is an object of the present invention, therefore, to increase substantially the number of tubes it is possible to use without encountering the above mentioned difficulties.

In accordance with a feature of the present invention, a plurality of groups of tubes connected in push-pull are arranged to impress their power into an output circuit common to all of them, each group being arranged to impress its power at an anti-nodal voltage point different to that at which the other groups impress their outputs.

This and other features of the invention will be explained by the aid of the accom-

panying drawings which show a step-by-step development of the invention.

Figs. 1 and 2 show the essentials of known forms of push-pull circuits using three electrode valves, for facilitating explanation of the invention;

Fig. 3 shows an embodiment of the present invention;

Fig. 4 shows a modification of the system of Fig. 3;

Fig. 5 is a simplified showing of the system of Fig. 3 with certain elements omitted for simplicity; and

Fig. 6 shows schematically a system derived as an extension of the systems of Figs. 3 and 5.

In Fig. 1 are shown the essentials of a familiar form of a push-pull circuit, the filament and anode current supply being omitted for the sake of simplicity. Two tubes 1, 2 have their respective grids G1, G2 and anodes P1, P2 connected in push-pull by output and input transformers IT, OT each comprising primary and secondary windings ITP, OTP and ITS, OTS respectively. The filaments F1, F2 are connected to a common point and a midpoint of a condenser C1 by which the grid circuits are tuned. The anode circuits of the tubes are tuned by a condenser C2 in parallel with the primary OTP of the output transformer OT. Balancing condensers B1, B2 are also shown, the function of which is to neutralize the interelectrode capacities of the valves in known manner. The input is fed through the primary ITP of transformer IT in the usual manner while the output is taken from the secondary OTS of the transformer OT.

If it be desired to increase the power to be handled by the arrangement shown in Fig. 1 then additional tubes may be connected in parallel with each of the tubes 1 and 2. If the arrangement be for the purpose of amplifying very high frequencies it will then be advisable to reduce C1 and C2 to very low values using them only as vernier condensers since the capacity of the valves in parallel will, without the added capacities of C1 and C2 be greater than is desired. Further in order to obtain a greater range of wave length

adjustment than is possible by adjustment of the small condensers C1 and C2 and also to overcome mechanical difficulties arising out of the shortness of the inductance coils on these high frequencies, it may be advantageous to resort to series tuning as shown in Fig. 2.

In Figs. 1 and 2 the voltage nodes have been indicated by the curve V. A study will show that whereas in Fig. 1 there is only one voltage antinode, there are two voltage antinodes in each of the two circuits in Fig. 2 namely, across the capacities C2 and C4 in the plate circuit and across C1 and C3 in the grid circuit. Further it will be seen on examination of Fig. 2 that both the input and output circuits become symmetrical about lines through the centre points of their inductance coils when the values of C3 and C4 are equal respectively to the values of C1 and C2 together with their respective parallel tube capacities. This suggests the possibility of feeding power into the output circuit across C4 in the same manner as it is fed in from the tubes connected across C2 and of exciting the grids of the tubes by the voltage across C3 in the same manner as the tubes shown in Fig. 2 are excited by the voltage across C1. Furthermore, the phase relations are such that the tubes excited by the voltage across C3 could feed into the output circuit across C4 adding to the power delivered by those already shown.

In accordance with the present invention therefore the condensers C3 and C4 are replaced by a second group of tubes in push-pull. The resulting circuit is shown in Fig. 3 wherein voltage nodes occur at the points midway between the inductance coils on each side of the tuned input and output circuits. Fine adjustment of tuning is made by variation of either C1' or C1'' in the grid circuit and by variation of either C2' or C2'' in the anode circuit. It is possible by varying the relative magnitudes of C1' and C1'', while maintaining the capacity of the two in series constant to keep the circuit tuned, to adjust the relative driving voltage on the grids of the two groups of tubes and so make them equal. Similarly by altering C2' and C2'' simultaneously it is possible to adjust the output circuit so that each group of tubes in push-pull works into the same impedance. Thus the two means of adjustment are afforded which are necessary to enable the load to be equally divided between the two groups of tubes. Although the output circuit has been shown inductively coupled to the load it could also be coupled by capacity as shown in Fig. 4.

It will now be evident that with an arrangement such as that shown in Fig. 3 the number of tubes it is possible to use in parallel has been quadrupled since it is now possible to use three or four in parallel in each

corner thus making a total of twelve or sixteen. A circuit of this type is particularly useful in the radio frequency amplification of ultra short waves namely, those having a wave length of less than 100 meters.

If now the balancing condensers and filament circuit be omitted for the sake of simplicity, it will be realized that Fig. 3 may be redrawn as shown in Fig. 5. An examination of this circuit will show that it is possible to extend it to any number of pairs of tubes provided always that the electrical distance between each pair is always half a wave length or a multiple thereof. Fig. 6 shows such a circuit extended to comprise four pairs of tubes. The system in this case resembles two artificial lines on which standing waves are set up; there being a group of tubes at every voltage loop. One of the artificial lines feeds the grids and the other receives power from the anodes. The power capacities with the tuning capacities in parallel form the parallel capacities of the lines and the tuning coils form the series inductances of the artificial lines. An alternative arrangement would be to insert the tuning condensers in series with the tuning coils instead of in parallel as shown in Fig. 6.

What is claimed is:

1. A circuit for translating electrical energy in which a plurality of groups of electron tubes are provided connected in push-pull the successive groups being separated one from the other by an electrical distance equal to one half wave length or an integral multiple thereof.

2. A circuit for translating electrical energy comprising two artificial lines one feeding the grids of a plurality of groups of tubes in push-pull and the other receiving power from the anodes of the said tubes and in which the shunt impedances of the said line comprise the interelectrode capacities of the tubes together with associated balancing and tuning capacities inserted at anti-nodal voltage points along the said lines.

3. A radio frequency amplifying circuit comprising a plurality of push-pull amplifying systems connected at successive voltage anti-nodal points in an output circuit common to all of said systems.

4. A circuit in which an assembly of electron discharge tubes in push-pull relation is connected in push-pull relation with another similar assembly.

5. A circuit in which a plurality of assemblies each comprising a plurality of tubes in push-pull relation are connected in push-pull relation with a plurality of similar assemblies.

In witness whereof, I hereunto subscribe my name this 18th day of August, 1930.

CHARLES E. STRONG.
